UNITED STATES PATENT OFFICE.

ADOLPH ANDERSON, OF CHICAGO, ILLINOIS, ASSIGNOR TO AURORA AUTOMATIC MACHINERY CO., OF CHICAGO, ILLINOIS, A CORPORATION OF DELAWARE.

GUN-CARRIAGE.

1,239,860.

Specification of Letters Patent. Patented Sept. 11, 1917.

Application filed August 16, 1916. Serial No. 115,306.

To all whom it may concern:

Be it known that I, ADOLPH ANDERSON, a citizen of the United States, residing at Chicago, in the county of Cook and State of Illinois, have invented certain new and useful Improvements in Gun-Carriages, of which the following is a specification.

The present invention relates to a gun carriage of the portable type, and more particularly adapted for use in connection with a machine or other small caliber gun.

The objects of the invention are, to provide a carrier which is capable of attachment to a motorcycle, or similar propelling means; to provide a floor or platform which will carry both the gun and a seat for the operator; to provide means for turning the floor, whereby the gun may be swung to point in various directions, and to maintain the operator in the same position with respect to the gun, no matter in what direction the gun may be turned, by reason of the gun and seat both being secured to the floor and hence held in the same relative position to one another; to provide means under the control of the operator for turning said floor; to provide a protecting wall attached to the floor and upwardly extending therefrom; to provide chambers adjacent said seat for carrying ammunition; to provide springs upon which the carriage is mounted; to provide means for rendering these springs substantially non-resilient when desired; to provide a light yet substantial framework upon which the rotatable floor which carries the gun is mounted; and to provide anti-friction means carried by the frame, and on which the floor or table travels in its revolving movements.

The invention further consists in the features of construction and combination of parts hereinafter described and claimed.

In the drawings:

Figure 1 is a plan view of the carriage of the present invention attached to a motorcycle;

Fig. 2, a section on line 2—2 of Fig. 1, looking in the direction of the arrows, and on a somewhat enlarged scale;

Fig. 3, a section on line 3—3 of Fig. 1, looking in the direction of the arrows, and on a somewhat enlarged scale;

Fig. 4, a detail plan view of the chassis of the carriage;

Fig. 5, a detail section through the pawls 55 and ratchets for rotating the floor of the carriage, and showing the shiftable member which acts to render the springs less resili-
ent;

Fig. 6, a perspective detail of the pawl 60 and ratchet mechanism; and

Fig. 7, a plan view of such mechanism.

Referring now to the drawings, the carriage of the present invention is shown in connection with a motorcycle 8, which may be of any suitable and well-known type, and the parts thereof will not be described in connection with the present invention, especially since it would be possible to attach this chassis to other propelling means than a motorcycle without departing from the spirit of the invention. The motorcycle is only illustrated to show one method which is deemed desirable for propelling the gun carriage.

The chassis of the carriage comprises a rod 9, made of one or more sections, which rod is connected to the motorcycle at one end 9^a thereof, and is bent into loop-formation, with its opposite end 10 also connected to the motorcycle, and at a point upon said rod is placed a mounting 11 for a wheel 12, said wheel being provided with the usual mud-guard 13. Extending across from the opposed portions of the rod 9 is a rod 14, from which extends a rod 15, which latter is joined to the motorcycle body. All of the above parts may be made of metal tubing, rendering the same light and strong.

Attached to the rods 9 and 14, as will be understood from Fig. 4, are holders 16, to which are secured leaf-springs 17. These springs have connected to each end thereof a member 18, formed on one end with studs 18^a, certain of which carry pipe sections 19^a, which, when assembled, form a ring 19. The remaining studs receive the ends of pipes, forming arms 20, and these arms, at their inner ends, are secured to a hub 21. There is thus formed a frame of spider construction. Carried by the members 18 are rollers 22, which project slightly above the surface of said members.

Resting above said frame, and upon the periphery of the rollers 22, is a platform or floor 23. Said floor has secured thereto a protective inclosure 24 of steel or other suitable material. Within this inclosure, and

carried by the floor 23, is a seat 25 for the operator, and upon each side of said seat is located a series of compartments for ammunition. Also carried by the floor 23 is a gun 27, which, in the form shown, is of the type known as machine gun, but may be of any suitable type with which the carriage of the present invention would be practicable of use.

Said gun is provided with the usual shield 28, and the gun and its associated mechanisms, together with the shield, are supported upon legs 29, the lower ends of which are mounted within sockets 30 attached to the floor. These legs are three in number, as shown, and can be simply slipped into the sockets 30, in which case no fastening means of any nature are used for holding the ends of the legs within the sockets. This renders the gun freely detachable from the floor and enables it to be very quickly removed from the carriage and placed upon the ground and then returned to the carriage. The tripod construction shown makes a very firm and substantial brace when the gun is mounted in the carriage or placed outside of the carriage.

In order to elevate the gun a worm 30 is employed, turned by a hand wheel 31, which operates upon a segment 32. The gun is capable of a swinging movement on a table 33 for a distance of about thirty degrees each way from the central position, independent of the movement of the floor, and can be raised or depressed about a center 34 and locked in such raised or depressed position by manipulation of a hand lever 34.

It has been previously explained that the floor 23 is revolved in order to bring the gun to various locations, and that by having the gun and seat for the operator both carried by the floor, the operator can always maintain the same relative position with respect to the gun, as the gun is swung by turning the floor. In order to turn the floor, I have provided a ratchet 35, which is secured to the floor 23, and this ratchet will be termed the upper movable ratchet. This ratchet, together with the floor, moves about a rod 36 as a pivot, which rod acts as a king bolt for these parts. I have also provided a ratchet 37, which is attached to the hub 21, and this ratchet will be termed the lower fixed ratchet.

Extending between the movable and fixed ratchets is an arm 38 and an arm 39, both pivoted to the rod 36. The arm 38 carries a pawl 40, which consists of an upper portion 41, having an acting end 42, and an acting end 43; and secured to this upper portion is a lower portion 44, having an acting end 45. The acting ends of the upper portion 41 co-operate with the movable ratchet 35, and the acting end of the lower portion 44 co-acts 65 with the fixed ratchet 37. The arm 39 car-

ries a ratchet 46, similar in construction and arrangement to the ratchet 40. The ratchet 40 is pivotally mounted by a pin 47 to the arm 38; and extending from the upper portion 41 of the ratchet 40 is an ear 48, to which is connected a rod 49, which in turn is joined to a pivoted lever 50 (Fig. 2), which lever is equipped with a pedal member 51 at its upper end, and is held normally in backward position by means of a spring 52.

Connected to the pawl 46 is an ear 53, similar to the ear 48. Joined to the ear 53 is a rod 54, similar to the rod 49, which rod 54 is connected to a lever 55, similar to the lever 50; and the lever 54 is formed with a pedal member 55 at its upper end similar to the pedal member 51. This pedal member 55 is held normally backward by means of a spring 56 similar to the spring 52.

It has been previously explained that the ratchet 35 is affixed to the table or floor 23, and hence upon movement of this ratchet the table will be turned. Assume that the pedal 51 (Fig. 1) is operated: This will pull the rod 49 in a forward direction, which swings the pawl 40 upon its pivot 47, bringing the acting end 42 of said pawl into engagement with the teeth of the ratchet 35. Continued movement of the pedal will swing the arm 38, which carries the pawl 40, about its center of movement, carrying the pawl with it, and turning the ratchet 35. As this ratchet is connected to the table, the table under such conditions will be turned 100 in a counterclockwise direction. When the pawl 40 is thus operated, the acting end 43 of the upper portion 41 and the acting end 45 of the lower portion 44 will be pulled out of engagement with the respective 105 ratchets with which said ends engage, but under this condition the operator would not move the pedal 55. Hence the ratchet 46 would remain in the position shown in Fig. 7, and in this position, the acting end 43 of the upper portion 41, and the acting end 45 of the lower portion 44 of the ratchet 46, would be in engagement with the teeth of the ratchets 35 and 37 respectively, and since the ratchet 37 is fixed, it is evident that the 115 pawl 46 will, under such conditions act to lock and retain the ratchet 35 in its moved position, thus acting to retain the table or floor in its moved or turned position.

When it is desired to operate the table or floor in a clockwise direction, the pedal 55 is actuated, in which instance the pawl 46 becomes the agency for turning the ratchet 35 and the table 23, and the pawl 40 becomes the agency for locking the ratchet 35 and table 23 in turned position.

It will thus be seen that by operating whichever of the pedals he desires, the operator may swing the floor carrying the gun to any desired position; and owing to the 130

fact that the seat for the operator is carried by the floor and turns therewith simultaneously with the gun, it is self-evident that the operator always remains in proper position with respect to the gun. This turning movement is especially advantageous when it is desired to turn the gun about for the purpose of retreats.

The foregoing described means for turning the table is extremely quick and simple of operation, enabling a speedy turning of the gun in the direction desired, and leaves the hands of the operator free at all times for manipulation of the gun and the handling of ammunition. During the actual firing of the gun, it is desirable to eliminate as far as possible the sway and movement of the carriage, and if the springs were made sufficiently strong to withstand this swaying movement, the device would be impractical for traveling over rough roads. On the other hand, with the spring of a nature to absorb the jars and jolts incident to travel, the gun carriage sways and vibrates to a degree which would be undesirable when the gun was being fired. I have therefore provided means for substantially taking out all resiliency from the springs, giving the gun carriage a practically rigid mount when desired.

The above means consists of a hand wheel 56, to which is joined the threaded rod 36, which has a threaded engagement with the hub 21 of the frame. The lower end 57 of this rod presses against a plate 58, which is connected to the holders 16 for the springs 17 (see Fig. 4). When the wheel 56 is turned, it moves the rod 36 downward, causing the end 57 to push against the plate 58, and this plate being joined to the holders 16, which in turn are joined to the chassis and incapable of downward movement, such action of the stem 36 will cause the hub 21, ring 19, and associated parts comprising the frame, to move upward, carrying the floor 23 and associated parts upward, thus stretching the springs 17 and substantially taking the resiliency out of them.

When it is desired to replace the ordinary resiliency in the springs, the wheel 56 can be quickly manipulated for this purpose, to draw up the rod 36 out of pressing engagement with the plate 58.

From the foregoing, it will be apparent that a gun carriage has been produced which enables a quick and easy shifting of the gun to various positions, and enables the operator to maintain a proper position with respect to the gun, no matter how the gun is shifted; and means are provided for making the gun carriage practically rigid and preventing the swaying thereof during firing. The seat for the operator, the gun, and the pedals which the operator actuates to revolve the floor, all remain in the same

relative position to one another as the floor revolves, so that the operator remains always in proper position to operate the gun and pedals.

I claim:

1. A gun carriage, comprising a chassis, a floor adapted to revolve with respect to said chassis, a gun carried by the floor, a gunner's seat carried by the floor, dog and ratchet mechanism for turning the floor, a pedal carried by the floor, a connection between said pedal and dog and ratchet mechanism, and said gear, seat and pedal all maintaining the same relative position with respect to one another as the floor is revolved, substantially as described. 70

2. A gun carriage, comprising a chassis, a floor adapted to revolve with respect to the chassis, a gun carried by the floor, a gunner's seat carried by the floor, a spring connection between the floor and chassis, an adjustable rod serving as a king bolt about which the floor turns, and said rod when adjusted acting to distend said springs to remove the resiliency therefrom, substantially as described. 80

3. A gun carriage comprising a chassis adapted for attachment to a propelling vehicle, a floor rotatable with respect to the chassis, a gun carried by the floor, a gunner's seat carried by the floor and located to the rear of the gun, means for rotating the floor, embodying a foot-operated member arranged forward of the seat, and said gun, seat and foot-operated member maintaining the same relative position with respect to one another during the rotative movements of the floor, substantially as described. 90

4. A gun carriage comprising a chassis, means for propelling the chassis, a floor rotatable with respect to the chassis, a gun carried by the floor, a gunner's seat carried by the floor and arranged to the rear of the gun, means for rotating the floor, embodying a foot-pedal arranged forward of the seat, and said gun, seat and pedal remaining in the same relative position with respect to one another as the floor is rotated, and said pedal when moved acting to turn the floor in a step by step movement, substantially as described. 105

5. A gun carriage comprising a chassis, means for propelling the chassis, a floor rotatably mounted with respect to the chassis, a gun carried by the floor, a gunner's seat carried by the floor and to the rear of the gun, means for rotating the floor, including companion actuating members arranged at the forward portion of the floor with one of said actuating members on each side of the gun, a connection between one of said actuating members and the rotating means for moving the rotating means to turn the floor in one direction, a connection between the other actuating member and rotating means 120

125

130

for turning the floor in the opposite direction, and said actuating members being arranged for operation by the feet of the user, and said seat, gun and actuating members remaining in the same relative position when the floor is turned, substantially as described.

6. A gun carriage comprising a chassis, a frame carried by the chassis, a floor mounted to revolve with respect to the chassis, a gun carried by the floor, a gunner's seat carried by the floor and to the rear of the gun, companion foot-pedals, one on each side of the gun arranged forward of said seat, a ratchet attached to the floor, a ratchet attached to the chassis concentric with the floor ratchet, companion arms extending to opposite sides of the ratchets and mounted to swing in a path concentric with the ratchets, an actuating pawl and a locking pawl on each arm, the actuating pawl coöperating with the floor ratchet and the locking pawl coöperating with the chassis ratchet, a connection between each of said arms and a foot-pedal, and said gun, seat and pedals all maintaining the same relative position with respect to one another as the floor is revolved, substantially as described.

7. A gun carriage comprising a chassis, a floor adapted to revolve with respect to said chassis, a gun carried by said floor, a gunner's seat carried by said floor and arranged to the rear of the gun, companion foot-pedals, one on each side of the gun arranged forward of said seat, a ratchet attached to the floor, a ratchet attached to the chassis concentric with the floor ratchet, companion arms extending to opposite sides of the ratchets and mounted to swing in a path concentric with the ratchets, an actuating pawl and a locking pawl on each arm, the actuating pawl coöperating with the floor ratchet and the locking pawl coöperating with the chassis ratchet, a connection between each of said arms and a foot-pedal, and said gun, seat and pedals all maintaining the same relative position with respect to one another as the floor is revolved, substantially as described.

7. A gun carriage comprising a chassis, a floor adapted to revolve with respect to said chassis, a gun carried by said floor, a gunner's seat carried by said floor and arranged to the rear of the gun, companion foot-pedals, one on each side of the gun arranged forward of said seat, a ratchet attached to the floor, a ratchet attached to the chassis concentric with the floor ratchet, companion arms extending to opposite sides of the ratchets and mounted to swing in a path concentric with the ratchets, an actuating pawl and a locking pawl on each arm, the actuating pawl coöperating with the floor ratchet and the locking pawl coöperating with the chassis ratchet, a connection between each of said arms and a foot-pedal, and said gun, seat and pedals all maintaining the same relative position with respect to one another as the floor is revolved, substantially as described.

ADOLPH ANDERSON.
